A. H. WILLETT

FIRE PAN

Filed Aug. 6, 1921

Alfred H. Willett Inventor

By his Attorney
Dunn, Leavitt & Techner

UNITED STATES PATENT OFFICE.

ALFRED H. WILLETT, OF WEST NEW YORK, NEW JERSEY, ASSIGNOR TO AMERICAN ARCH COMPANY, A CORPORATION OF DELAWARE.

FIRE PAN.

Application filed August 6, 1921. Serial No. 480,195.

My invention relates to fire pans for furnaces fired with fuel in gaseous, vaporous, or suspended condition, and is of especial advantage for fire pans or "flash pans" of oil burning locomotives. The invention is particularly concerned with the supply of air for combustion to the fire pan and the furnace, my aim being to provide for heating the air and for cooling the furnace or fire pan structure, so as to improve the combustion and the fuel economy and to preserve the furnace against too rapid deterioration under the intense heat. In the embodiment of my invention hereinafter described (the best at present known to me), both of the above-stated objects are effected; and this is done in such a way that the furnace structure is cooled by air that is supplied to the fire pan to support combustion, and is therefore heated.

It is also an object of my invention to provide an improved construction for the floor of the flash pan of an oil burning locomotive whereby it can be made of a plurality of bricks similar to those used in the arches. Such a construction is now known in the art as "sectional." I, therefore, provide a "sectionally" constructed bottom or floor for the flash pan.

The foregoing, together with such other objects which may appear hereinafter or are incident to my invention, I obtain by means of a construction which is illustrated in preferred form in the accompanying drawings.

In the drawings, Fig. 1 shows a vertical longitudinal section through the fire box and fire pan or flash pan of an oil fired locomotive boiler with my invention applied thereto.

Fig. 2 shows a cross section through the fire pan, taken as indicated by the line 2-2 in Fig. 1.

Fig. 3 is a fragmentary view similar to Fig. 2, showing a modified arrangement for air admission and the use of a greater number of tubes for supporting the bricks of the floor than is shown in the other figures.

Fig. 4 is a fragmentary view similar to Fig. 1, showing still another arrangement for air admission.

The locomotive fire box 5 shown in Fig. 1 is of a familiar type. It is provided with the usual sectional fire arch 6 extending rearward and upward from the lower portion of the tube sheet 7, and consisting of fire brick

8 supported on fore and aft water circulation tubes 9 connected between the tube sheet 7 and the rear wall 10 of the fire box. At the bottom of the fire box 5 is a fire pan structure 11 whose general form and construction are also familiar in the art. It may be briefly described as comprising a metal floor sheet or "shelf" 12 extending inward, from the bottom of the mud ring 13, and a metal trough 14 with sloping sides 15, 15 extending fore and aft within and below the inner edges of the shelf 12. The front end 16 of the trough 14 slopes rather steeply, and has an opening 17 into which projects an oil burner 18, and through which an initial supply of air for combustion is also admitted. The rear end 19 of the trough 14 is shown as vertical, and serves to arrest or baffle the jet, blast, or stream of fuel and air from the burner 18, mix it up, and throw it forward and upward into the superjacent combustion chamber or furnace proper of the fire box 5. The fire pan structure 11 has a refractory fire brick lining, shown as thickest at and above the rear end 19 of the trough or fire pan proper 14. It has also a solid refractory-lined floor or shelf of narrow width at its rear end.

Prior to my invention, the practice has been to admit a large supply of air (additional to that admitted at the burner 18, and usually exceeding it in amount) to the fire pan 14 in a large, cold blast. The coldness of this considerable supply of air affects the operation, economy, and useful life of the furnace unfavorably, since it tends to chill the flaming fuel stream below the combustion temperature, to chill the walls of the furnace and the fire pan locally as it strikes them in one spot or another with the eddying and swirling of the flames, and to produce uneven combustion. By preheating this main air supply on its way into the fire pan, I promote thorough, uniform and efficient combustion, and obviate various drawbacks and disadvantages of prior practice.

Referring, now, to the lower portion of Figs. 1 and 2, it will be seen that the floor 20 of the fire pan trough 14 is of a sectional refractory construction, somewhat resembling that of the fire arch 6. This floor 20 comprises a couple of fore and aft rows of fire brick 22 (similar to the usual type of middle row fire arch brick 8) supported by

substantially horizontal fore and aft tubes 25 that serve as air passages in the floor. At their forward ends, the tubes 25 extend and open out through a downward extension 26 of the front trough wall 16; while at their other ends, they open rearward into the fire pan 14 through a chamber or compartment 27 that opens upward into said fire pan. The chamber 27 serves as a clean-out 10 hopper for refuse, slag, etc., from the super-jacent fire pan 14, and its rear wall 28 is hinged at 29 to permit of its being swung rearward and upward for removal of accumulated slag and ash from time to time. 15 The whole floor 20 being heated by the burning fuel stream above it, the air entering the tubes 25 at the forward end of the fire pan 14 is thoroughly heated as it passes rearward through them; and in this preheated 20 condition, it is discharged into the burning fuel stream above the floor and mingles and unites with it.

In the flooring 20 supported by the tubes 25 are a number of openings 30 through 25 which air passes directly upward to the fire pan 14, being preheated in its passage. As shown, these openings are individually rather narrow, so that the air passing through them shall be more effectually preheated by radiation and conduction from the brick. Air is also admitted to the compartment 27 and the fire pan 14 beneath the floor 20, through a multitude of small openings 33 in the forward wall 34 of said compartment. 30 This air (as well, indeed, as that admitted through the openings 30) is preheated by coming against the floor 20 on its way to the openings through which it enters the fire pan 14,—as also by radiation and con- 35 duction downward from the floor. As shown, the air entering the fire pan 14 through the holes 30 and 33 is directed against the floor 20 and brought in contact with it by means of an air intake casing or 40 chamber 35 beneath the floor, in front of the compartment 27. Air is admitted to the casing 35 through transverse openings 36 in its lower side or wall, and these openings are controlled and the passage of the air through 45 50 the casing 35 regulated by adjustable dampers 37 pivotally mounted in the openings and operable in unison by a common rod 38 pivoted to their depending actuating crank arms 39. The rod 38 may, if desired, 55 be connected with the usual firing valve (not shown) that controls and regulates the burner 18.

Not only is the combustion air supply preheated in the floor passages 25, in the 60 floor openings 30, and in the casing 35, but the floor 20 is cooled and protected against the ill effects of overheating by this same air.

In the modified arrangement illustrated 65 in Fig. 3, the openings 46 for admitting

air to the casing 35 are in its opposite sides or walls instead of in its bottom (as in Figs. 1 and 2), and the admission and passage of air through the casing is controlled by adjustable vertically swinging dampers 47 piv- 70 oted at their upper edges just above these openings.

In this figure there is also shown the use of a greater number of tubes 25 for supporting the brick 22^a than is shown in the other 75 figures, which arrangement is somewhat more substantial and secure.

In the modified arrangement illustrated in Fig. 4, the openings 56 for admitting air to the casing 35 are in its forward end or wall 80 instead of in its bottom (as in Figs. 1 and 2), and the adjustable swinging damper 57 that controls and regulates this opening also overlaps the forward ends of the tubes 25 and controls and regulates the admission 85 and passage of air through them.

What I claim is:

1. The combination of a fire pan with fore and aft air supply tubes extending out through one end thereof discharging into the 90 pan at their other ends, and refractory flooring supported by said tubes, and means for admitting an additional supply of air to said pan through said refractory flooring.

2. The combination of a fire pan with fore and aft air supply tubes receiving air at the forward end thereof and discharging into the pan at their rear ends, refractory flooring supported by said tubes, and an air intake casing beneath the floor thus formed, 100 with means for admitting air heated in said casing into the fire pan.

3. The combination of a fire pan with fore and aft air supply tubes receiving air at the forward end thereof and discharging into the pan at their rear ends, refractory flooring supported by said tubes, and an air intake casing beneath the floor thus formed, 105 with means for admitting air heated in said casing into the fire pan, and means for regulating the passage of air through said casing.

4. The combination of a fire pan with fore and aft air supply tubes receiving air at the forward end thereof and discharging into the pan at their rear ends, refractory flooring supported by said tubes, and an air intake casing beneath the floor thus formed, 115 with means for admitting air heated in said casing into the fire pan including a plurality of openings upward through said floor, and 120 a damper-controlled opening in the wall of said casing for admission of air thereto.

5. The combination of a fire pan with fore and aft air supply tubes extending from the forward end thereof rearward into a de- 125 livery compartment opening upward into the rear of said pan, refractory flooring supported by said tubes, and an air intake chamber beneath the floor thus formed in front of said compartment, with means for 130

admitting air heated in said compartment to the fire pan including openings upward through said floor and openings rearward into said compartment.

5 6. The combination of a fire pan with air supply tubes having one end open to the atmosphere and discharging into the fire pan at the other end and a refractory floor supported by said tubes, and means permitting 10 an additional circulation of air between and around said tubes.

7. In combination with a fire pan, air supply tubes having one end open to the atmosphere and discharging into said pan at the 15 other end, a refractory floor supported by said tubes, and an air directing casing beneath said floor.

8. In combination with a fire pan, air supply tubes having one end open to the atmosphere and discharging into said pan at the 20 other end, a refractory floor supported by said tubes, an air-directing casing beneath

said floor, and air-inlets between said casing and said pan.

9. In combination with a fire pan, air supply tubes having an air-intake end and discharging into said pan at the other end, a refractory floor supported by said tubes, a casing beneath said tubes and floor, air-inlets between the casing and said pan, an air-intake at an end of the casing, and an adjustable damper at the air intake end of the tubes and casing.

10. The combination with a fire pan of a plurality of tubes underlying said pan, said tubes being open at their ends for admitting air freely into said fire pan, and externally controlled means auxiliary to said tubes for admitting an additional supply of air into 40 said fire pan.

In testimony whereof, I have hereunto signed my name.

ALFRED H. WILLETT.
